UNITED STATES PATENT OFFICE.

JOHN P. ONDERDONK, OF PHILADELPHIA, PENNSYLVANIA.

STOCK FOR FIRE-ARMS.

SPECIFICATION forming part of Letters Patent No. 319,613, dated June 9, 1885.

Application filed March 25, 1885. (No model.)

To all whom it may concern:

Be it known that I, JOHN P. ONDERDONK, a citizen of the United States, residing at Philadelphia, in the county of Philadelphia, and State of Pennsylvania, have invented a new and useful Improvement in Fire-Arms, of which the following is a specification.

My invention relates to improvements in the manner of resisting the recoil of fire-arms; and the object of my invention is to lessen in a greater or less degree the shock of the recoil. I attain this by the device illustrated in the accompanying drawings, in which—

Figure 1 is a side view of a gun-stock containing my improvement. Fig. 2 is a top view of the same. Fig. 3 is a cross-section of Fig. 1. Fig. 4 is a cross-section of a stock embodying the union of the construction shown in Figs. 1 and 2.

Similar letters refer to similar parts throughout the several views.

In Fig. 1, A is an ordinary gun-stock, into which I saw or make in any manner slightly-curved slits or incisions B B, with a serpentine slit, C. All these slits or incisions terminate at or near the butt plate or end of the stock D. This, however, is not essential, as they may be cut clear through the end of the stock D, and then be secured together by any suitable means. These slits or incisions may be cut from the top of the stock down through the bottom; as represented in Fig. 2, in which A is the stock, E E the slits or incisions, F the serpentine slit, and D the butt plate or end of the stock. These slits or incisions may be cut both ways in the same stock, as shown in cross-section, Fig. 4. The serpentine slits C and F are cut so as to keep the surface of the stock entire and leave no opening through it; but this is not essential, for they may be varied or made curved as the others, and a small opening left in the side or top of the stock, or both, as the case may be. The slits or incisions make the wood between them springs,

which receive and deaden the recoil of the gun. 45 The parts between the slits or incisions may be made separately, and then be put together and suitably secured to form a gun-stock, or they may be made of metal or other material and put together to form a stock, without departing from the spirit of my invention. The slits or incisions are slightly curved, so that the parts between them will move readily and yield to pressure or concussion. They may be made without a curve, but would not act so readily. 50 Of course, the slits or incisions may be made in any part of the gun-stock and in any position thereon, and of various forms and dimensions, as the case may require.

Having fully described my invention, what I desire to claim and secure by Letters Patent is—

1. A gun-stock having slits or incisions through the stock, arranged substantially parallel, substantially as shown and described. 65
2. A gun-stock having slits or incisions through the stock, arranged substantially parallel and curved, substantially as shown and described.
3. A gun-stock formed of substantially parallel strips, separated from each other by a space and united at their ends, which strips form springs to resist the recoil of the gun, substantially as shown and described. 70
4. A gun-stock having slits or incisions through the stock from side to side and from top to bottom, forming strips or rods, substantially as shown and described. 75
5. A gun-stock having slits or incisions through the stock, the curvature of which gradually decreases from top or bottom toward the center, substantially as shown and described. 80

JNO. P. ONDERDONK.
